UNITED STATES PATENT OFFICE.

GUSTAV A. CARLSON, OF CHICAGO, ILLINOIS, ASSIGNOR TO THE BOYE NEEDLE COMPANY, OF CHICAGO, ILLINOIS, A CORPORATION OF ILLINOIS.

SCREW DRIVER.

Application filed November 19, 1920. Serial No. 425,192.

To all whom it may concern:

Be it known that I, GUSTAV A. CARLSON, a citizen of the United States, residing at Chicago, in the county of Cook and State of Illinois, have invented a new and useful Improvement in Screw Drivers, of which the following is a specification.

This invention relates particularly to screw-drivers constructed wholly of metal; 10 and the primary object is to provide an improved screw-driver of this type which can be manufactured at minimum cost and which is staunch and durable.

The invention is illustrated in its preferred embodiment in the accompanying drawing, in which—

Fig. 1 represents a plan view of a screw-driver constructed in accordance with the invention; Fig. 2, a side elevational view of 20 the same; Fig. 3, a broken sectional view taken as indicated at line 3 of Fig. 2; Fig. 4, a broken sectional view similar to Fig. 3, but with one of the parts shown in Fig. 3 removed; Fig. 5, a broken lower outer 25 side view of the member shown in Fig. 4; Fig. 6, a broken elevational view of the end portion of the loop-forming portion of the strip employed in the construction of the screw-driver; and Fig. 7, a broken plan 30 view of the part shown in Fig. 6.

The improved screw-driver preferably is formed wholly from an integral strip of steel, which preferably is of flat form throughout. This strip has one end formed 35 to provide a flat blade 1 and has the opposite end portion formed to provide a loop-form handle 2. The blade 1 has a screw-driver tip 1^a, and has a shank portion 1^b which is offset at one side of the plane of 40 the blade 1. The continuation of the strip is so formed as to provide the loop 2. Thus, continuing from the shank portion 1^b, there is a divergent or oblique portion 2^a, a loop side 2^b, a rear loop-end 2^c, a loop side 45 2^d, a convergent or oblique portion 2^e opposite the portion 2^a, and a shank portion 2^f parallel with a bearing against the offset shank portion 1^b. The portion 2^f constitutes 50 the extreme end portion of the loop-forming part of the steel strip. The portion 2^f is provided with a reduced extension 2^g which affords a rivet. This rivet extends thru a

central perforation 3 located at the junction of the blade 1 and the offset shank portion 1^b. The end of the rivet-portion 2^g is upset or riveted in the perforation 3, the perforation being provided with a countersink 3^a to accommodate the upset portion of the rivet.

As may be noted from Figs. 1 and 3, the extremity of the loop-forming portion of the strip finds a bearing against a shoulder 4 which is afforded by offsetting the shank-portion 1^b from the plane of the blade 1. The rivet portion 2^g preferably forms an angle with the portion 2^f which is slightly obtuse, as will be understood from Fig. 3. After the riveting operation, any excess metal may be ground off, leaving the upset end of the rivet flush with the surrounding surface of the metal. The screw-driver may be nickel-plated, if desired, thus practically obliterating the joints and giving a finished appearance.

It may be added that a screw-driver may be formed in this manner more cheaply and of neater appearance than could be accomplished by spot-welding the extremity of the loop-forming portion of the strip and the shank portion 1^b.

The device is strong and durable. It preferably is formed of a high grade of steel, so that the blade may be suitably tempered.

What I regard as new, and desire to secure by Letters Patent, is—

1. A screw-driver comprising a steel strip having one end affording a blade and having the other end portion affording a loop-form handle, the extremity of the loop having an integral rivet portion extending through a perforation in the shank at the base portion of the loop and riveted therat.

2. A screw-driver comprising a steel strip having one end affording a blade and having the other end portion affording a loop-form handle, the metal of the strip being offset to provide a bearing for the extremity of the loop-form portion of the strip said extremity having a reduced bent extension riveted in a perforation through the shank at the base portion of the loop.

GUSTAV A. CARLSON.
